CONVERTIBLE BEDSTEAD

Sander Baker and Nick Stefano, Cleveland, Ohio,
said Stefano assignor to said Baker

Application April 13, 1956, Serial No. 578,141

1 Claim. (Cl. 5—331)

The present invention relates generally to bedsteads and more particularly to a convertible bedstead in which detachable side panels or guards are mounted on a bed-frame to provide a junior bed or youth bed.

In general, cribs are provided for infants and youth beds are provided for young children who have outgrown a crib, but who are still not old enough to be trusted in an adult size bed. Thus, children who are from 3-7 years old will tend to fall out of bed unless a guard or fence of some sort is provided. The youth bed is intermediate in size between the crib and the adult bed, and is provided with elevated side guards to prevent the child from accidentally falling out of bed. However, when the child has outgrown the youth bed, the youth bed must be discarded in favor of an adult bed. This represents a considerable and unnecessary expense, in view of the fact that the child can utilize the youth bed only for about four years.

It is the primary object of our invention to provide a youth bed which is quickly and easily convertible to a conventional adult bedstead when the child has outgrown the need for it, thus making it unnecessary to purchase a new adult bed for the grown child.

Another object of our invention, is to provide a convertible bedstead of the character described in which the side panels are so constructed and arranged that they can be mounted on conventional adult bed frames without requiring any extensive modification thereof.

A further object of our invention is to provide a bedstead of the character described in which said side panels include a hinged drop-leaf for permitting convenient ingress to and egress from the bed.

Still another object of our invention is to provide a bedstead of the character described in which the conventional spring and mattress serve to space and stabilize the side panel structure.

Other objects and advantages of our invention will become apparent during the course of the following description.

In the accompanying drawings forming a part of this specification and in which like numerals are employed to designate like parts throughout the same,

Fig. 1 is a perspective view of a bedstead embodying the features of our invention.

Fig. 2 is a fragmentary cross-sectional view taken on line 2—2 of Fig. 1.

Fig. 3 is a fragmentary cross-sectional view taken on line 3—3 of Fig. 1.

Referring more particularly to the drawings, the bedstead is seen to comprise a supporting frame 10, and a headboard 11.

The frame 10 is of the type commonly referred to as a "Hollywood" bed frame which is formed of fabricated angle iron. The frame includes a pair of horizontally-spaced parallel rails 14 and 15, each of which is provided with a pair of rigid transversely-extending cross-bars 16. Each of the rails 14, 15 has secured thereto a pair of depending legs 17.

In assembling the frame 10, the cross-bars 16 of the

right rail 14 are disposed in overlapping, nested relationship to the opposed cross-bars 16 of the left rail 15. The overlapped cross-bars are linearly adjusted so that the rails 14, 15 are parallel to each other and are properly spaced to receive the bedspring and mattress (not shown). The opposed cross-bars are then secured to each other by means of a suitable clamp 18 to provide a rigid frame.

The rails 14, 15 define parallel sills or support ledges 19 and short vertically extending retainer walls 20. The bedspring is supported on the ledges 19 and is maintained against transverse movement by the retainer walls 20. It will be understood that the body-supporting bedspring and mattress are slightly longer than the rails 14, 15 so that the foot-ends 21 of the rails do not project beyond 15 the body-supporting members.

The head-end 22 of each of the rails 14, 15 has fixedly secured thereto a vertically-extending plate 23. The head-board 11 is secured to the frame 10 by means of bolts or screws 24 which connect the headboard to the plates 23. The headboard 11 includes a pair of vertically-extending posts 25 rigidly connected to each other by a plurality of cross-members 26 to provide a framework for the decorative portion 27 of the headboard which may be upholstered and suitably embellished, as desired. The headboard 11 thus provides an upright rigid extension of the frame 10.

It will be noted that the foregoing describes a conventional Hollywood bedframe and headboard which are assembled and secured to each other to provide an adult bedstead such as is in common and widespread use.

In order to make the bedstead suitable for use as a youth bed, we provide a right side panel 28 and a left side panel 29 on the bedstead. It will be understood that under certain conditions, such as when the bedstead is located with one side against a wall of the room, only one of said side panels might be desired. However, as herein described, a pair of such panels are shown. Inasmuch as the left panel 29 is a mirror image of the right panel 28, it will be sufficient to describe the structure of only 40 the panel 28.

The panel 28 includes a vertically-extending baseboard 30 which is substantially coextensive with the rail 14 and which rests upon and is supported by the upper edge of the wall 20 of the rail 14. The head-end 31 of the baseboard 30 extends into overlying relationship to the post 25 of the headboard 11 and is secured thereto by means of readily removable wood-screws 32, so that the baseboard is rigidly connected to the headboard. The foot-end of the baseboard 30 would normally, due to its remoteness from the point of securement, have some degree of transverse movement relatively to the frame 10. In order to prevent any such outward transverse movement or displacement of the baseboard 30, we provide a retainer element 33 which is secured to the baseboard 30 adjacent the foot-end thereof. As best seen in Fig. 2, the retainer 33 is L-shaped and has the stem portion 34 thereof secured in a recessed portion 35 of baseboard by means of a threaded fastener 36. The flange portion 37 of the element 33 is substantially coplanar with the inner face 38 of the baseboard 30 and is disposed in face-to-face abutment with the surface of the upright wall 20 provided by the rail 14. Thus, the foot-end of the baseboard is retained against outward displacement by the element 33. When the bedspring and mattress are placed 55 on the frame 10, they serve to prevent any inward displacement of the baseboard and also serve to maintain the retainer element 33 in firm abutment with the frame 10 so that the baseboard will not rattle or move when the bed is being used.

70 The panel 28 also includes a drop-leaf 39 which is hingedly secured, as at 40, in edge-to-edge abutment with the baseboard 30 as it is not necessary that the

drop-leaf be stabilized by the spring and mattress in the manner that the baseboard is. The hinged connection 40 between the baseboard and the drop-leaf is sufficient to provide the necessary support and stability for the drop leaf 39. The baseboard 30 is preferably sufficiently high to extend to a level which is slightly below the level of the body-supporting mattress; the drop leaf 39 is sufficiently high to provide the necessary safeguard to prevent the child from accidentally rolling off the bed.

As best seen in Fig. 3, a spring-loaded catch 41 is secured to the headboard post 25 in the path of movement of a striker element 42 which is secured to the upper edge of the drop-leaf 39. In closed position, the drop-leaf is held by the catch 41 as shown in Figs. 1 and 3. When the catch is released, the drop-leaf 39 will fall or can be rotated to the lowered position shown in dotted outline in Fig. 1. In the lowered position, the drop-leaf permits normal ingress to or egress from the bed without obstruction. When the drop-leaf is raised back to its closed position, the striker 42 cams the catch 41 and the catch 41 then resets to automatically secure the drop-leaf in its upright position. By placing the catch 41 on the post 25, the catch is easily accessible, without interference or obstruction by the bedclothes, and at the same time it is in a location which minimizes the possibility of it being accidentally opened by the bodily movement of the sleeper.

When the child has reached an age where the safeguard of the side-panels is no longer required, the removal of the screws 32 permits the entire side-panel assembly to be removed and thereby provides a conventional adult bedstead for continued use by the growing child. There is thus no necessity for purchasing a single-purpose type of junior bed which must subsequently be discarded as the child outgrows it. It will readily be observed that if a Hollywood frame bedstead is already available, the purchase of the side-panels only will suffice to convert the bedstead into a youth bed in the manner heretofore described. In order to effect such a conversion, it is only necessary to attach the catch 41 to the headboard and to use screws 32 to secure the panel assembly to the post 25 of the headboard. No expensive or extensive

modification of the conventional Hollywood bedframe is required.

It is to be understood that the form of our invention, herewith shown and described, is to be taken as a preferred example of the same, and that various changes in the shape, size and arrangement of parts may be resorted to, without departing from the spirit of our invention, or the scope of the subjoined claim.

Having thus described our invention, we claim:

10 A bedstead comprising a supporting frame including a pair of spaced longitudinally extending parallel rails, each of said rails having a horizontally extending inwardly directed bed spring-supporting ledge and a vertically extending retainer wall, ground-engaging supports depending from each of said rails to maintain said supporting frame above ground level, an upright headboard secured to said pair of rails adjacent the head end thereof, an upright base-panel disposed in edge-to-edge abutment with the edge of said retainer wall of one of said rails and coextensive with said rail from a point beyond the head end of said rail to a point intermediate the ends of said rail, means for securing one end of said base-panel to said head-board, retainer means depending from the edge of said base panel adjacent the other end thereof and coplanar with the inwardly directed face of said base-panel, said retainer means abutting the inner face of said retainer wall to prevent outward displacement of said other end of said base-panel from said rail, a drop-leaf hingedly secured in edge-to-edge abutment with said base-panel and having one end thereof extending to a point beyond the head end of said rail, and means provided on said headboard in the path of pivotal movement of said drop-leaf for releasably securing said drop-leaf to said headboard.
